UNITED STATES PATENT OFFICE

ALBERT PFLUGER AND KONRAD HAAGE, OF ESSLINGEN-ON-THE-NECKAR, GERMANY

MECHANICAL HAMMER

Application filed September 24, 1927, Serial No. 221,726, and in Germany July 15, 1926.

Our invention relates to mechanical percussive tools, for instance to hand-rammers, and more particularly to tools, in which an internal combustion engine is provided for operating the tool.

It is an object of our invention to provide a tool in which the energy imparted to the tool is partly utilized for supplying the cylinder of the engine with a fresh charge of combustible mixture.

To this end we so determine the length of a part of the engine, for instance its piston rod, with respect to the total length of the engine, for instance its cylinder, that the difference in the lengths of the two parts is equal to the suction stroke of the engine. In the case of a hand-rammer the total length of the piston and its rod is made less than the total length of the cylinder plus the tup, for an amount equal to the suction stroke so that, with the rammer in its initial position, in which the tup and the lower end of the piston rod are resting on the pavement, the cylinder head is above the piston for a distance equal to the suction stroke.

It is another object of our invention to provide means for controlling the operation of the inlet valve and the ignition of the engine simultaneously, and to this end we provide an operating lever for the inlet valve which is connected with contacts or other suitable means for effecting the ignition upon closing the inlet valve.

It is still another object of our invention to provide means for drawing the charge of mixture into the engine cylinder before starting the operation of the tool and to this end we equip a piston of the engine, or its rod, with a handle, or handles, for reciprocating the piston in the cylinder when the tool is in its initial position.

It is still another object of our invention to provide means for automatically controlling the inlet valve of the engine in conformity with the pressure in its cylinder, and to this end we provide a clutch in connection with the hand lever by which the valve is held on its seat and provide means of throwing out the clutch and permitting the valve to be

opened when the pressure in the cylinder exceeds a given limit.

In the accompanying drawings, contrivances embodying our invention are illustrated diagrammatically by way of example.

In the drawings:

Figs. 1 to 5 illustrate a contrivance having a comparatively simple valve operating mechanism;

Figs. 6 to 8 illustrate the cylinder head of a contrivance having a more elaborate valve gear.

Figs. 1, 2, 3, and 4 are longitudinal sections showing the contrivance in various stages of its operation;

Fig. 5 is an axial section of the cylinder head of this contrivance, drawn to a larger scale;

Fig. 6 is an axial section of the cylinder head and the elaborate valve gear, taken in the same plane as Fig. 5;

Fig. 7 is an axial section taken at right angles to Fig. 6 and viewed from the left in that figure;

Fig. 8 is a plan view of the cylinder head, partly in section on the line VIII—VIII in Fig. 7, and drawn to a smaller scale.

Referring now to the drawings, and first to Figs. 1 to 5, these illustrate a pavement ram but it is understood that our contrivance may be used for any other operation.

1 is the cylinder of an internal combustion engine, 2 is a tup which is shown integral with the cylinder but might be secured to it by detachable means, if desired, 3 is the cylinder head, 4 are handles secured to or formed integral with, the cylinder head, 5 is a piston in the cylinder 1, 6 is its piston rod which is free to slide in the tup 2, 7 are brackets secured to the piston rod, and 8 are springs secured to the brackets at one end and to the handles 4 at the other. The extension of the cylinder 1 to which the tup is secured or with which it is integral, as shown, is slotted for the brackets 7, 7.

Referring now to Fig. 5, 10 is a control lever for the valve mechanism which is fulcrumed to an extension of the cylinder head 3 at 9, and 11 is a coiled spring which is secured to the cylinder head, or to one of its

handles 4, as shown, and tends to return the lever to its initial position after it has been depressed. 12 is a cam projecting inwardly from the fulcrum 9 and engaging a slot in the hollow stem 13 of a combined exhaust and inlet valve 14, 15 is a choke tube inserted in the upper end of the extension, 16 is a jet through which fuel is supplied to the bore 17 of the choke tube from any carburetor or supply, not shown, 18 is a secondary-air passage in the base of the head extension, 19 are passages in the hollow stem 13 for allowing the secondary air to enter the cylinder past the valve 14 when it is open, and 20 are exhaust slots in the cylinder which are adapted to be uncovered by the piston 5. The stem 13 of the valve 14 is slotted for the jet 16 so that its movement is not interfered with. 10' is a contact on the lever 10, 4' is a corresponding contact on the handle 4, and 4'' is a cable connecting the contact 4' with a sparking plug as shown at 45 in Fig. 6.

Assuming that the rammer is in its initial position as shown in Fig. 1, in which, as explained in the introduction, the clearance between the piston 5 and the cylinder head is equal to the suction stroke, the inlet valve 14 is lifted by the spring 11 through the medium of the lever 10 and the cam 12, the piston 5 is raised by hand through the medium of the brackets 7, and returned to its initial position, drawing a fresh charge into the cylinder.

When the control lever 10 is depressed the valve 14 which had been held open by the spring 11, is seated. The space above the piston 5 is filled with an explosive mixture and is ignited by automatic means connected with the control lever. Such means are not shown in these figures but will be described with reference to Figs. 6 to 8. The contrivance is in the position illustrated in Fig. 1, with the tup 2 and the piston rod 6 resting on the pavement or the like. When the mixture is ignited, the charge expands and raises the cylinder with the tup against the tension of the springs 8, 8. When the cylinder has attained the position in Fig. 2, the exhaust slots 20 are uncovered but the expanding gases still act on the cylinder so that it is further raised into the position illustrated in Fig. 3 in which the brackets 7 of the springs 8 prevent further upward movement of the cylinder with respect to the piston 5. The momentum of the cylinder and tup will now lift the contrivance away from the surface on which it is supported by its piston rod, and it will jump into the position illustrated in Fig. 4. In the meantime the gases above the piston have been completely expanded and for the most part discharged through the exhaust slots. The springs 8 will now contract and pull the piston 5 to the end of its stroke, the residue of gases which is intercepted in front of the piston after it has moved past the exhaust slots 20 being discharged past the

valve 14 which has been moved away from its seat by the spring 11.

When the parts have lost their momentum they will return to the initial position as shown in Fig. 1 and while the piston 5 is moving away from the cylinder head it will draw a fresh charge into the cylinder which is ignited as described by depressing the lever 10.

It will be understood that in this contrivance it is necessary to release the control lever immediately after it has been operated so that the spring 11 is free to open the valve 14 at the right time. In the valve gear illustrated in Figs. 6, 7 and 8, means are provided in connection with the control lever for automatically disconnecting it from the valve so that the lever can be depressed for any length of time without interfering with the operation of the valve.

Referring now to Figs. 6, 7, and 8, identical parts as the cylinder 1, its head 3, the handles 4, etc., have been designated by the same reference numerals as in Figs. 1 to 5.

Fig. 6 shows the control lever 10 partly depressed. Its end is curved so as to extend in parallel with one of the handles and to be able to enter a recess in the upper face of the handle. 24 is a cam which is free to turn on the fulcrum 9 of the lever 10 and is adapted to engage the valve spindle 27 with its forked end 26. 25 is an abutment on the cam 24 and this abutment is adapted to be engaged by a latch 22. The latch 22 is adapted to turn about a pin 21 in the lever 10, and a spring 23 on the lever tends to hold the latch 22 engaged with the abutment 25 so that the lever 10 and the cam 24 are positively engaged.

28 is a collar which is engaged from below by the fork-shaped end of the cam 24, 30 is a spring inserted between the moveable collar 28 and a collar 29 on the end of the valve spindle 27, and endowed with some initial pressure. 42 is a spring which is weaker than the spring 30 and is inserted between the top surface of the collar 29 and a cap 31 which is screwed on the guide 38 of the valve stem.

33 are chambers formed in the cylinder head 3 on either side, 32 are pipes connected with the carburetor, not shown, at one end and with the chambers 33 at the other, 34 are passages connecting the chambers 33 with chambers 35, one on each side of the guide 38 which is extended into a wall projecting on either side of the spindle 27, as will appear from Fig. 8. 36 are perforations in each chamber 35 which are closed on the outside of the chamber by a plate-shaped valve 37 so that fluid can only flow from the chambers 35 but not in reversed direction.

39 is a chamber formed in a hollow extension of the cylinder head 3. The lower part of the spindle guide 38 projects into this hollow extension. 40 are exhaust ports or pas-

sages in the wall of the extension and 41 is a plate valve closing the passages.

45 is a sparking plug inserted in the cylinder head 3, 44 are its electrodes, and 43 is its contact. The contact is connected with the sparking plug by wires, not shown, and adapted to be closed by the cam 24 after the control lever 10 has performed a given stroke.

46 is a bore in the cylinder head, 47 is a piston adapted to slide in a cylinder on the cylinder head against the action of a spring 48, and 49 is the rod of the piston which rod is adapted to engage a rearward extension 50 of the latch 22.

15 It is not necessary that the pipes 32 and the chambers to which they are connected should be duplicated as illustrated by way of example.

20 The operation of the valve gears is as follows:

In the position illustrated in Fig. 6 the lever 10 has been depressed until the valve 40 has been closed, compressing the spring 42 while no substantial tension is exerted in the 25 stronger spring 30. Upon further depression of the lever, a certain pressure will also be exerted on the stronger spring 30 and, at the same time the contact 43 will be closed by the cam 24 so that a spark will be generated at the electrodes 44 of the sparking plug and the mixture in the cylinder will be ignited. The pressure of the expanding mixture is transmitted to the piston 47 which will rise in its cylinder and through the medium 35 of its piston rod 49, disconnect the latch 22 from the cam 24 so that the cam is free to turn on the fulcrum 9 independently of the lever 10 and the valve 40 is lifted from its seat by the joint action of the springs 30 and 40 42.

45 When the valve 40 has been opened and the piston is expelling the exhaust gases from the cylinder they will be discharged through the passages 40, lifting the spring plate 41. When the suction period begins the valve 41 closes automatically and the valve 37 opens so that mixture is drawn into the cylinder from the passages or ports 36.

50 Automatic means might be provided for operating the valve 14 but it has been found preferable to control the contrivance by hand.

55 Other means than those shown and described may be provided for supplying mixture to the cylinder. In general, we wish it to be understood that we do not desire to be limited to the exact details of construction shown and described for obvious modifications will occur to a person skilled in the art.

60 We claim:—

1. A mechanical percussive tool comprising a cylinder, a tup on said cylinder, a piston in said cylinder, a piston rod connected with said piston, means for supplying combustible mixture to said cylinder, and means

for igniting the mixture, the length of said cylinder, measured from its inner end to the striking face of said tup, and the length of said piston and piston rod, measured from the inner face of said piston to the end of said rod, being so determined that their difference is equal to the suction stroke of said piston.

2. A mechanical percussive tool comprising a cylinder, a tup on the lower end of said cylinder, a piston rod connected with said piston, means for supplying combustible mixture to said cylinder, and means for igniting the mixture in said cylinder, the length of said cylinder, measured from its inner end to the striking face of said tup, and the length of said piston and piston rod, measured from the inner face of said piston to the end of said rod, being so determined that their difference is equal to the suction stroke of said piston.

3. A mechanical percussive tool comprising a cylinder, a tup on said cylinder, a piston in said cylinder, a piston rod connected with said piston, an inlet valve on said cylinder, means for supplying combustible mixture to said inlet valve, means for igniting the mixture, and a handle for operating said valve and said igniting means in unison, the length of said cylinder, measured from its inner end to the striking face of said tup, and the length of said piston and piston rod, measured from the inner face of said piston to the end of said rod, being so determined that their difference is equal to the suction stroke of said piston.

4. A mechanical percussive tool comprising a cylinder, a tup on said cylinder, a piston in said cylinder, a piston rod connected with said piston, means for supplying combustible mixture to said cylinder, means for igniting the mixture, the length of said cylinder, measured from its inner end to the striking face of said tup, and the length of said piston and piston rod, measured from the inner face of said piston to the end of said rod, being so determined that their difference is equal to the suction stroke of said piston, and means extending through said cylinder and operatively connected with said piston for moving said piston and said cylinder by hand.

5. A mechanical percussive tool comprising a cylinder, a tup on said cylinder, a piston in said cylinder, a piston rod connected with said piston, an inlet valve on said cylinder, means for supplying combustible mixture to said inlet valve, means for igniting the mixture, a handle for operating said valve and said igniting means in unison, a clutch intermediate said handle and said valve, automatic means for holding said clutch in its operative position, and means controlled by the pressure in said cylinder for throwing out said clutch, the length of

said cylinder, measured from its inner end to the striking face of said tup, and the length of said piston and piston rod, measured from the inner face of said piston to the end of said rod, being so determined that their difference is equal to the suction stroke of said piston.

In testimony whereof we affix our signatures.
